SEWING MACHINE BELT DRIVE

Joseph Galkin, New York, N. Y.

Application June 14, 1937; Serial No. 148,150

2 Claims. (Cl. 74—242.10)

This invention relates to a belt drive and belt tensioning mechanism to take the place of pitman drives in sewing machines and more particularly to a mechanism suitable for forming a tensioned driving connection between the main and needle-bar actuating shafts of high speed sewing machines.

An object of this invention is to provide an attachment for sewing machines having upper and lower shafts driven in timed relation, whereby a tensionable belt drive for said shafts is shielded by a housing which is integrally secured to the sewing machine frame and has a removable end cover whereby the driving mechanism may be exposed to view in its entirety for tensioning the belt.

Another object of this invention is to provide in a sewing machine having upper and lower shafts driven in timed relation by a belt, a hollow overhanging enclosure for said shafts having a transversely movable belt tensioning element and a closeable opening in an end wall of said enclosure, thereby forming a repeatedly tensionable shielding belt drive adapted for high-speed sewing machines.

Another object of this invention is to provide means for moving the transverse tensioning element to cause the belt to be automatically tensioned.

With the above and other objects in view, the invention will be hereinafter more particularly described, and the combination and arrangement of parts will be shown in the accompanying drawing and pointed out in the claims which form part of this specification.

Reference will now be had to the drawing, wherein like numerals of reference designate corresponding parts throughout the several views, in which:

Figure 1 is a fragmentary side view of a sewing machine frame to which my belt tensioning attachment has been applied.

Figure 2 is a cross-sectional view, the section being taken as on line 2—2 in Figure 1.

Figure 3 is an enlarged assembly view of the tensioning screw, slide and clamping bolt for actuating a toothed idler wheel.

In the illustrated embodiment of the invention, the numeral 10 indicates a hollow overhanging frame of a sewing machine having upper and lower shafts 11 and 12 mounted thereon, to rotate in parallel and in timed relation to each other.

The shafts 11 and 12 have been made sufficiently long to extend out from the end wall 13 of the

frame 10 to make it possible to mount the belt driving mechanism thereon and to be entirely outside the sewing machine frame. Secured to the end wall 13 by means of screws 14 and a flange 15 is a housing or casing 16 having an open end face 17. A cover plate 18 has been removably secured to the housing 16 by screws 19. As shown in Figure 1, the cover plate 18 has an opening at its upper end serving to receive the hub of the pulley on the shaft 11. The cover plate 18 may thus be swung about the shaft 11 without removing the pulley. Fixedly mounted on the shafts 11 and 12 are wheels, 20, 20, each having a plurality of teeth 21, 21. A canvas belt 22, having transverse wire projections 23 fixed thereto and meshing with the wheel teeth 21 has been rotatably mounted on the toothed wheels 20 so as to cause the lower shaft to drive the upper shaft in timed relation.

For the purpose of this invention, the end wall or transverse support 13 of the frame 10 has been grooved to provide a guideway 24, positioned transverse of said frame. A slide 25, having an elongated slot 26, has been movably mounted on the guideway 24 and is secured to the frame 10 by a bolt 27, passing through the slot 26, and threaded in the end wall 13 of the frame 10. An idler wheel 28, having a plurality of teeth 29, similar to the teeth 21, has been freely rotatably mounted on a stud 30, projecting at one end from the slide 25, and in rotative engagement with the driving side of the belt 22.

A screw 31 has been threadably secured in a tapped hole in one end of the slide 25, opposite the stud 30 and axially in alignment with the slot 26 and perpendicular to the bolt 27. The inner end of the screw 31 rests against a coil spring 35, which contacts the body of the bolt 27, as best shown in Figure 3. By actuating the screw 31 in the slide 25, it is possible to move the slide 25 and idler wheel 28 transversely of the frame 10, as determined by the guideway 24, towards the opposite side of the belt and thus increase the tension in the belt 22. The spring 35 tends to constantly move the slide 25 and the idler wheel 28 in a transverse direction to tighten the belt 22 automatically. To permit the spring 35 to function continuously as a belt tightener, I draw up the clamping bolt 27 to less than its maximum tightened capacity, so as to leave a minute clearance between the washer 36 at the head of the bolt and the slide 25. This adjustment permits the spring 35 to move the slide 25 and the idler wheel 28 and causes the belt to be automatically tensioned.

It is to be noted that, while I have shown the entire belt tensioning mechanism in the form of an attachment which may be secured to existing sewing machines having a hollow upright frame 5 **10**, that I may install my tensioning mechanism inside the hollow frame **10** and provide an end opening and a cover in said frame (not shown) but similar to the end opening **17** and cover **18** to the end face **13** of the sewing machine frame. 10 It will then be possible, by removing such end cover from the frame, to tension the belt with ease and precision while the operator is fully shielded from contact with said mechanism.

In accordance with the patent statutes I have 15 described and illustrated the preferred embodiment of my invention, but it will be understood that various changes and modifications can be made therein without departing from the spirit of the invention as defined by the appended 20 claims.

It is to be noted that if a non-tensionable belt drive were used, that when the belt became stretched and considerably worn, it would jump over a tooth and upset the timing arrangement, 25 with the result that the sewing machine parts become broken and considerable time and money is lost in repairing the machine. The disclosure herein prevents such an occurrence and is a desirable advantage in the operation of sewing machines having shafts driven in timed relation. 30

I claim:

1. In a belt tensioning device for a sewing machine having a hollow overhanging frame including a transverse support, a casing extending 35 longitudinally from said transverse support and forming an enclosure for a belt, said sewing machine having a belt drive-shaft and a belt driven-shaft which extend into said casing, said casing having an open end face at a point spaced from 40 said transverse support, said support having a transverse slideway, a slide movable on said slideway and having an elongated slot, said slide being secured to said frame by a bolt coacting with said slot, a toothed idler wheel rotatably mounted at 45 one end of said slide, a screw means threadably positioned in said slide for adjusting said slide

and idler wheel along said guideway, toothed wheels mounted on said shafts and being connected by said belt, said belt having means for engaging with said teeth to rotate said wheels in timed relation, said idler being adapted to bear 5 against a side of said belt, a removable cover plate for the open end face of said casing, said cover plate having an opening and one of said shafts extending through said opening and permitting said cover plate to be swung about said 10 shaft, whereby said idler wheel and said slide mechanism may be shielded or whereby it may be viewed in its entirety when tensioning said belt.

2. A belt tensioning device for a sewing machine having a hollow overhanging frame which includes a transverse support, comprising a casing extending longitudinally from said transverse support and forming an enclosure for a belt, said sewing machine having a belt drive-shaft and a belt driven-shaft which extend into said casing, said casing having an open end face at a point spaced from said transverse support, said support having a transverse slideway, a slide guided movably in said slideway, releasable means 25 fixed to said transverse support and adapted to secure said slide to said frame, a toothed idler wheel rotatably mounted at one end of said slide, screw means operatively connected with said slide and coacting with said releasable means for adjusting said slide and its idler wheel along said guideway, wheels having teeth mounted on said shaft extensions, said belt having means for engaging with said wheel teeth, said wheels being connected by said belt and being rotated in timed 30 relation, said idler being adapted to bear against a side of said belt, a removable cover plate for the open end face of said casing, said cover plate having an opening and one of said shafts extending through said opening beyond said casing and 35 said cover plate, said opening permitting said cover plate to be swung about one of said shafts, whereby said idler wheel and said slide mechanism may be shielded or whereby it may be viewed in its entirety when tensioning said belt. 40
